US0D1053287S

(12) **United States Design Patent** (10) **Patent No.:** **US D1,053,287 S**
(45) **Date of Patent:** **** Dec. 3, 2024**

(54) **EXERCISE EQUIPMENT WITH TREAD**

(71) Applicant: **I-TECH USA, INC.**, Farmington Hills, MI (US)

(72) Inventor: **Dominic Simenthi**, Ernakulam (IN)

(73) Assignee: **I-TECH USA, INC.**, Farmington Hills, MI (US)

(**) Term: **15 Years**

(21) Appl. No.: **29/946,572**

(22) Filed: **Jun. 10, 2024**

Related U.S. Application Data

(63) Continuation of application No. 29/834,267, filed on Apr. 11, 2022, now Pat. No. Des. 1,030,925.

CLAIM

The ornamental design for exercise equipment with tread as shown and described.

DESCRIPTION

FIG. 1 is a top perspective view of exercise equipment with tread;

FIG. 2 is a bottom perspective view thereof;

FIG. 3 is a top plan view thereof;

FIG. 4 is a rear elevational view thereof;

FIG. 5 is a front elevational view thereof;

FIG. 6 is a bottom plan view thereof;

FIG. 7 is a right-side elevational view thereof; and,

FIG. 8 is a left-side elevational view thereof.

The broken lines in the drawings form no part of the claimed design.

1 Claim, 3 Drawing Sheets
